Design No. 3,667, dated September 28, 1869.

DESIGN FOR A BUST OF ALEXANDER VON HUMBOLDT.

The Schedule referred to in these Letters Patent and making part of the same.

To all whom it may concern:

Be it known that I, HENRY BERGER, of the city, county, and State of New York, have invented a new and original Design for Bust of Alexander von Humboldt; and I do hereby declare the following to be a full, clear, and exact description thereof, which will enable those skilled in the art to make and use the same, reference being had to the accompanying drawing, which represents a perspective view of this design.

This invention relates to the design for a bust of Alexander von Humboldt, consisting of the head A,

neck B, shoulders C, and body D, as shown in the drawing.

What I claim as new, and desire to secure by Letters Patent, is—

The design for a bust of Alexander von Humboldt, as shown and described.

This specification signed by me, this 23d day of August, 1869.

HENRY BERGER.
